United States Patent Office.

ALBERT THOMPSON, OF NORWAY, MAINE, ASSIGNOR TO HIMSELF AND
G. T. WHEELER, OF RIDGWAY, PENNSYLVANIA.

Letters Patent No. 97,002, dated November 16, 1869.

IMPROVED FILE.

The Schedule referred to in these Letters Patent and making part of the same.

To all whom it may concern:

Be it known that I, ALBERT THOMPSON, of Norway, in the county of Oxford, and State of Maine, have invented a new and useful Improvement in Files; and I do hereby declare that the following is a full, clear, and exact description of the construction and operation of the same, reference being had to the accompanying drawings, making a part of this specification, in which—

Figure 1 is a plan view, and

Figure 2 is a side elevation.

This invention consists in a single-cut flat file, so constructed that when a stroke in one direction has been made, the file may be turned over, and a return cutting stroke be made with it, thus very much expediting the labor of filing a saw or other article.

In the drawings—

A is a flat file, of the kind ordinarily used for sharpening saws. In this operation, the stroke can only be made upward, or against the clamp, as, if made in the opposite direction, the saw is caused to tremble; hence, when a file of the usual construction is used, after making an up stroke, the filer has to carry his instrument down again to get it into the proper position for the next up stroke.

To avoid the loss of time consequent upon making these return motions, is the object of my invention.

My file is made with one set of teeth, *a a*, inclined in one direction on one side, while the other or opposite set, *b b*, runs in a direction at an oblique angle

thereto on the opposite side. As a consequence, after making a stroke with the teeth *a*, all the filer has to do before making another stroke, is to turn the file over in his hands and lower the upper end. It is then ready for cutting in the reverse direction to the former stroke and upon the same tooth of the saw.

Between each stroke, the file has simply to be turned side for side, which is an operation more quickly performed than to carry it back; hence, with this file, a saw can be sharpened much more quickly than with one of the ordinary sort.

I am aware that there is a patented file in which the teeth are reverse on opposite sides. These teeth, however, are made in separate pieces from the file, and then fastened upon it in some suitable manner.

In my invention, however, the teeth are cut in the body of the file.

Having thus described my invention,

What I claim as new, and desire to secure by Letters Patent, is—

An improved single-cut flat file, having teeth whose planes of strike or prolongation from the opposite sides shall cross each other, but whose dip or pitch on the two sides shall be shown in longitudinal section, as lying in the same or parallel planes, all as shown and described.

ALBERT THOMPSON.
